UNITED STATES PATENT OFFICE

HARRY WALTON FEATHERSTONE, OF EAST SWANZEY, NEW HAMPSHIRE

FLUID DISPENSING CAN

Application filed March 19, 1930. Serial No. 437,126.

This invention relates to new and useful improvements in cans and has for its primary object the provision of a device of the above stated character especially adapted for dispensing cleaning fluid and is arranged to deliver a small quantity of fluid directly to the sponge or cleaning element used for removing spots from fabric or otherwise employed in cleaning.

10 Another object of this invention is the provision of means to be engaged and pressed by the sponge or cleaning element while held in one hand to moisten the latter with the cleaning fluid, leaving the person's other 15 hand free to handle the fabric being cleaned and also obviate the necessity of a person removing the eyes from the part of the fabric being cleaned.

20 A further object of this invention is the provision of means for supplying a limited amount of fluid to the sponge or cleaning element during each operation of the device and will protect the major portion of the cleaning fluid from fire when exposed to the 25 flame of a match or the like.

25 A still further object of this invention is the provision of a can of the above stated character which will be simple, durable and efficient, and which may be manufactured and sold at a comparatively low cost.

30 With these and other objects in view as will become more apparent as the description proceeds, the invention consists in certain novel features of construction, combination and arrangement of parts as will be hereinafter more fully described and claimed.

35 For a complete understanding of my invention, reference is to be had to the following description and accompanying drawings, in which:

40 Figure 1 is a vertical sectional view illustrating a can constructed in accordance with my invention.

45 Figure 2 is a top plan view illustrating the same, and

50 Figure 3 is a horizontal sectional view of the device.

55 Referring in detail to the drawings, the numeral 1 indicates a container having a filling neck 2 in its top wall to permit clean-

ing fluid to be placed in the container and is normally closed by a removable top 3. The top wall of the container 1 is off-set centrally thereof and apertured to receive a dispensing device 4.

60 The dispensing device 4 includes a cylinder 5 located in the container 1 and is provided at its upper end with a reduced neck 6 that extends through the opening in the top of the container and is internally and externally 65 screw-threaded. A shoulder 7 is formed by the reduced neck 6 and abuts the inner face of the top wall of the container and a locking nut or gland 8 is threaded to the neck 6 against the outer face of the top wall and cooperates 70 with the shoulder 7 in tightly securing the cylinder in the container. The lower end of the cylinder 5 is spaced slightly from the bottom of the container and is closed by a removable valve seat 9 having a passage 10 to admit 75 fluid from the container to the interior of the cylinder. A valve cage 11 is located in the cylinder on the valve seat 9 and supports a spring pressed check valve 12 adapted to prevent escape of fluid from the cylinder back 80 into the container during the operation of the device. A piston 13 is located in the cylinder and engages one end of a coil spring 14 while the other end of said spring seats on the valve seat 9 about the cage 11. The piston 85 13 is secured to a hollow piston rod or tube 15 which extends entirely through the piston 13 and outwardly of the upper end of the cylinder 5 and container 1 and has a valve seat formed in its upper end to be engaged by a 90 check valve 16 located in a cup 17. The cup 17 is detachably secured to the tube 15 as clearly shown in Figure 1 and is provided with a perforated disk 18 to form a seat for the spring 19 of the check valve 16. A packing 95 20 is positioned in the neck 6 about the tube 15 and is retained therein by a packing gland 21 threaded in the neck 6. A suitable vent 22 is provided at the upper end of the cylinder 5 and also above the fluid in the container to permit air to escape from the upper portion of the cylinder during the reciprocation of the piston.

100 In operation, after the container 1 has been filled with cleaning fluid, the piston 13 is

5 moved upwardly and downwardly several times by pressing on the cup 17 which draws fluid into the lower portion of the cylinder 5 on the first upward stroke of the piston and
10 on the next downward stroke, the fluid in the cylinder is then forced through the tube 15 into the cup 17 and retained therein by the check valve 16. It being understood that the check valve 12 will permit fluid to enter the lower portion of the cylinder 5 on the upward movement of the piston 13 and will prevent said fluid from returning to the container 1 on the downward stroke of the piston. It is also to be noted that it is only necessary to move the piston downwardly by pressing on the cup 17 as the piston will return to its normal position by the influence of the spring 14 when the cup 17 is released. A person cleaning fabric or the like, employs a sponge or a suitable cleaning element 24 and holds the same in one hand while the fabric being cleaned is held in the other hand and usually upon a support and to moisten the cleaning element 24, the person presses the same into the cup 17 with sufficient force to move the piston downwardly in the cylinder 5 which will force the fluid from the lower end of the cylinder into the cup by way of the tube 15 to moisten the cleaning element. Therefore it
25 will be seen that it is only necessary to employ one hand to actuate the device or to place the desired amount of cleaning fluid on the cleaning element 24 and that the major portion of the cleaning fluid will be housed or
30 protected when brought in close proximity to the flame from a match or the like.

While I have shown and described the preferred embodiment of my invention, it will be understood that minor changes in construction, combination and arrangement of parts may be made without departing from the spirit and scope of the invention as claimed.

Having thus described my invention, what I claim is:

45 A device for dispensing cleaning fluid to a cleaning element comprising a container having the top wall centrally offset and apertured, a cylinder in the container, an internally and externally screw threaded neck formed on one end of the cylinder and extending through the offset of the top wall, said neck of a diameter smaller than the diameter of the cylinder to provide a shoulder having engagement with the inner face of
50 the offset, an apertured plate in the neck at the formation of the latter with the cylinder to provide a seat, a nut threaded to the neck and against the outer face of the offset, a tube extending through the neck into the cylinder and slidably relative thereto, a packing material in the neck, a stuffing nut threaded in the neck to force said material against the tube and apertured plate, a piston on the tube within the cylinder, tension means between
55 the piston and cylinder, said cylinder having

60 a vent opening adjacent the neck and located within the offset of the top wall, a valve between the cylinder and container, a cup-shaped member secured to the end of the tube located exteriorly of the container, a perforated plate secured in the cup-shaped member and spaced from the bottom thereof, and a check valve between the apertured plate and last mentioned end of the tube.

65 In testimony whereof I affix my signature. 75
